UNITED STATES PATENT OFFICE.

NELSON A. NEWTON, OF KALAMAZOO, MICHIGAN.

WAGON-SPRING.

SPECIFICATION forming part of Letters Patent No. 325,355, dated September 1, 1885.

Application filed May 12, 1884. Renewed March 13, 1885. (No model.)

To all whom it may concern:

Be it known that I, NELSON A. NEWTON, a citizen of the United States, residing at Kalamazoo, in the county of Kalamazoo and State of Michigan, have invented new and useful Improvements in Wagon Springs and Gear, of which the following is a specification.

This invention relates to springs and running gear for vehicles; and it consists in the construction and combination of parts herein-after set forth and claimed.

In the accompanying drawings, Figure 1 represents a plan view of my improved springs and the adjacent parts of the wagon-gear. Fig. 2 represents a detail side view, partly in section, of a portion of the gear, showing the manner of attaching one of the springs thereto. Fig. 3 represents a detail perspective view of one of the springs, and Fig. 4 represents a bottom view of a part of the wagon-body with the springs attached thereto.

The same letters indicate the same parts in the several figures of the drawings.

A designates the axles of a vehicle; B, the bolster to which the front axle is attached; C, the fifth-wheel, which allows said front axle to turn independently of said bolster; D, the reach, and D' the brace-rods extending from said reach to the rear axle.

30 I make use of no side bars, but employ instead four torsion-springs, E, of peculiar construction, two of which are attached to the bolster B and the other two to the rear axle.

For this purpose the outer end of each spring 35 E is provided with an eye, *t*, which is connected by a link, *v*, with the fastening-clip *i*, attached to the bolster or axle, as the case may be. Each of these springs consists, first, of a rod, *r*, extending for some distance from the

eye *t* parallel to said reach and then bent at 40 right angles inward, and, second, of a flat bar forming a continuation of said rod and bent at its inner end, so as to be parallel to said reach, the part of said bar which is at right angles to said reach being marked *a*, and the part which 45 is parallel to said reach being marked *c*. These parts *c* are securely fastened to the underside of the frame *P* of the wagon-body *F*. Each spring is made in one piece throughout, and passes near the bend in the cylindrical rod *r* 50 through a block, *f*, which is attached to the side pieces of the wagon-body frame *P*.

Each pair of springs will form at its end of the wagon an approximately rectangular resilient supporting-frame operating by torsional elasticity, and the combined effect of said springs is to efficiently support both sides and all corners of the wagon-body, thereby making side bars superfluous.

Having thus described my invention, what 60 I claim as new, and desire to secure by Letters Patent, is—

A series of wagon-springs, in combination with the wagon body and gear, each spring consisting of an outer rod, *r*, and an angular 65 inner bar which is attached to said wagon-body, this angular inner bar being composed of a flat longitudinal portion, *c*, and a flat lateral portion, *a*, at right angles thereto, all parts of the spring being in one piece, substantially as described.

In testimony whereof I have hereunto set my hand in the presence of two subscribing witnesses.

NELSON A. NEWTON.
